UNITED STATES PATENT OFFICE.

MARIE F. HASEMEIER, OF WOODWARD, OKLAHOMA.

ELECTROTHERMAL BATH CABINET.

Application filed January 25, 1922. Serial No. 531,617.

To all whom it may concern:

Be it known that I, MARIE F. HASEMEIER, a citizen of the United States, residing at Woodward, in the county of Woodward and State of Oklahoma, have invented a new and useful Electrothermal Bath Cabinet, of which the following is a specification.

The present invention relates to bath cabinets particularly of the thermo-electrical type, wherein the patient is treated by heat and light rays produced entirely by electricity.

An essential object of the invention is the production of a cabinet of the above stated character possessing such a construction and arrangement of parts by which the treatment aimed at is more efficiently effected.

It is also an object of the invention to produce a cabinet which is simple, sanitary and may be manufactured economically, while at the same time having the necessary features enabling the electric therapeutic bath treatments to be practiced upon scientific principles.

With the above and other objects in view the invention further resides in the sundry details of construction, combination and arrangement of parts more specifically pointed out in the following specification and in the appended claims.

In this specification and the annexed drawings the invention is disclosed in the form in which it is considered to be the best, but the invention is not limited to such form because it is capable of being embodied in other forms; and it is to be understood that in and by the claims following the description herein it is intended to cover the invention in whatever form it may embody within the scope thereof.

In the drawings:—

Figure 1 is a perspective view of the cabinet,

Figure 2 is a horizontal cross-sectional view of the cabinet taken substantially on line 2—2 of Figure 3,

Figure 3 is a longitudinal sectional view of the cabinet, and

Figure 4 is a transverse sectional view of the cabinet taken substantially on line 4—4 of Figure 3.

Referring more in detail to the drawings with like numerals referring to corresponding parts throughout the several views, 1 designates an elongated horizontally extending cabinet comprising a bottom wall *a*, top wall

b, side walls *c* and end walls *d* and *e*. The bottom wall *a* is supported above the ground or floor on suitable legs 2 having casters or other means permitting the cabinet to be moved about from place to place at will. The end wall *e* is of considerable less height than the end wall *d* and this provides an entrance *X* for the cabinet. The top wall *b* is hinged as at 8 and extends from the end wall *d* over the major portion of the cabinet and preferably terminating at a point distant from the vertical plane of the end wall *e*. The hinged top *b* allows the operator to readily adjust the different electrical appliances used within the cabinet either before or after receiving the patient therein or for permitting other treatment, such as massaging or the like, to be administered to the patient while in the cabinet.

When using the cabinet of this invention, the patient is in a reclining position in order that the entire body may be relaxed and the normal strain on the functioning organisms relieved as much as possible so that the beneficial results from the treatment may be best obtained. Also the cabinet is designed to readily receive and treat those patients who are unable to assume any other position than reclining.

To this end, spaced rollers 3 are transversely arranged in the interior of the cabinet 1 and journalled as at 4 in the side walls *c* thereof, and above the bottom wall *a* in a horizontal plane substantially in alignment with the upper edge of the end wall *e* as best illustrated in Figure 3. A table 5 of non-conducting heat material rests upon these rollers and may be reciprocated thereon to move in and out of the opening *X* of the cabinet. The table 5 is preferably of greater length than that of the cabinet to provide an extension 5^a, normally projecting from the cabinet, with suitable supporting legs 6 having casters or other means admitting the legs to move relative to the floor or base. The extension 5^a of the table provides a head rest for the patient and is also formed with a handle 7 which enables it to be moved in and out of the cabinet.

As can be observed from the drawings, the table 5, when in its normal position in the cabinet, definitely divides the cabinet into upper and lower chambers *m* and *n*, respectively, the upper being the patient receiving chamber and the lower being the

heat chamber. The table 5 is provided with a series of perforations 10 through which the heat from the chamber *n* may pass and to allow the proper distribution of the heat 5 into the chamber *m* and around the patient. An electric heater 9 is disposed on the bottom wall *a* of the cabinet 1 below the table 5 and may be shifted to any position desired along the length of the cabinet in order to 10 obtain a greater degree of heat at that part of the patient's body where it is most needed or desirable. When certain parts of the body are to be intensely treated to the partial exclusion of others, certain of the perforations 10 may be closed by any suitable means, and in the present instance have 15 shown sheets of asbestos 11 to be laid over the perforations. Furthermore, while only one heater 9 is shown, any desired number 20 may be used as occasion may require.

In the rear portion of the chamber *m*, preferably on the rear wall *d*, is arranged means 12 for treating the body with electrical light rays. This means may be of any 25 desired type known to electrical therapeutics, but in the embodiment of the present invention such means are used as will give a "violet ray" because of the well known therapeutic value thereof. This means 12 is 30 placed in the rear portion of the chamber *m* adjacent the feet of the patient being treated for the additional purposes of utilizing the heat therefrom to draw the blood towards the feet and quicken the circulation. The light means 12 may be covered 35 by protecting cage 13 made of non-conducting heat material for the purpose of preventing the feet or other portions of the body of the patient from coming in contact therewith and being burnt or otherwise 40 injured.

On each side of the cabinet 1 adjacent the entrance end X are provided auxiliary chamber members 14 and 15 which communicate 45 with the chamber *m* of the main cabinet 1 through the elongated openings 16 in the side walls *c* and arranged immediately above the table 5. Within the chambers 14 and 15 and, preferably, at the lower edge of the openings 16 are provided arm rests 17 consisting, preferably but not necessarily, of horizontal strips covered or padded with felt, asbestos or other suitable non-conducting heat material. The chambers also communicate 55 with the heat chamber *n* of the cabinet through the openings 18 positioned below the table 5 for the purpose of permitting the heat to pass into the auxiliary chambers and upwardly through the arm rests whereby the arms are subjected 60 to the heat treatment. The passage of the heat into the chambers 14 and 15 is controlled by suitable means 19, such as swinging doors, operated by cranks 20 extending through the end wall *e*. A suitable lock 65

means 21 is provided for maintaining the doors in adjusted position. By providing the auxiliary chambers 14 and 15 the arms of the patient are subjected to an individual treatment which is of particular importance 70 in certain cases, and, furthermore, permits the patient to assume a more comfortable position while being treated. Each of the arm chambers 14 and 15 have suitably positioned therein above the arm rests 17 a light 75 ray discharging device 22 similar in all respects to the light ray discharging device 12, except that it may be of less power.

The cabinet may be made of metal, wood or any suitable material but has its interior walls lined with asbestos or other suitable material to retain the heat within the cabinet. 80

In operation, the table 5 is drawn out 85 of the cabinet through the entrance X sufficiently to enable the patient to be placed thereon in a reclining position. The extension 5^a of the table may receive a pillow upon which the head of the patient may 90 rest. The operator then opens the top wall *b* of the cabinet and adjusts the heater 9 to a position within the cabinet to produce the best results in the treatment of this patient. If it is desired to use more than 95 one heater another may be inserted in position, or if it is desired to close up certain of the perforations 10 in order to concentrate the heat on a particular portion of the body of the patient, strips 11 are suitably arranged on the top surface of the 100 table. The table is then pushed into the cabinet to the position shown in the drawings. The operator then arranges the patient on the table and a blanket is placed over the entrance opening X in order that the heat may be retained in the cabinet, but the head of the patient, however, is not covered by the blanket so that the cool air 105 of the room may be inhaled.

If the arms of the patient are to receive 110 intense treatment his arms are inserted into the cabinets 14 and 15 through the openings 16 and the heat controlling doors 19 are suitably adjusted to an open position, by operating the cranks 20 in order that the desired degree of heat may pass up into the arm treating chambers. The light ray discharging devices 12 and 22 are then set 115 into operation. As the treatment progresses the operator may open and close the top wall *b* of the cabinet in order to make suitable adjustments or to administer additional 120 treatment.

From the above a clear understanding 125 may be had of the form of my invention as at present devised. It is of course understood that various changes in details of construction may be made without departing from the spirit thereof.

What I claim as novel and my invention 130

and upon which Letters Patent are prayed is:

1. A therapeutic bath cabinet of the character described comprising a horizontally extending body portion having an entrance opening at one end, a table upon which the patient may lie slidably extending through said entrance opening into said cabinet and dividing the cabinet into upper and lower chambers, a heater disposed in said lower chamber to be adjustable along the length of said chamber, said table having a plurality of openings therein through which the heat may pass upwardly into said upper chamber and around the patient on the table. 5
2. A therapeutic bath cabinet of the character described comprising a horizontally extending body portion having an entrance opening at one end, a table upon which the patient may lie slidably extending through said entrance opening into said cabinet and dividing the cabinet into upper and lower chambers, a heater in said lower chamber to be adjustable along the length thereof, said table having a plurality of openings therein through which the heat may pass upwardly into said upper chamber and around the patient on the table, and means for closing certain of the openings in said table whereby the heat from the heater may be concentrated at desired portions of the body. 10
3. A therapeutic bath cabinet of the kind described comprising a horizontally extending body portion having an entrance opening at one end, a table slidably extending through the opening into said cabinet upon which the patient may lie, said table having one end thereof normally projecting outside of the entrance opening and providing a head rest, therapeutic treating means arranged in the lower part of the cabinet, therapeutic light treatment means arranged in the upper part of the cabinet, and a movable top to the cabinet permitting the operator to adjust the therapeutic means in the cabinet and for administering other treatment to said patient. 15
4. A therapeutic bath cabinet of the kind described comprising a body portion having an entrance opening at one end, a table upon which the patient may lie insertable through said opening into said cabinet and dividing said body portion into upper and lower chambers, a heating means in the lower chamber of said cabinet, auxiliary compartments on each side of the cabinet and com- 20
- municating with the body portion through openings adjacent the table through which openings the arms of the patient may extend, arm rests in said compartments and passages communicating the lower heat chamber of said body portion of the cabinet with said auxiliary compartments, whereby the heat from said heat chamber will pass upwardly into said compartments around the arms of said patient. 25
5. A therapeutic bath cabinet of the kind described comprising a body portion having an entrance opening at one end, a table upon which the patient may lie insertable through said opening into said cabinet and dividing said body portion into upper and lower chambers, a heating means in the lower chamber of said cabinet, auxiliary compartments on each side of the cabinet and communicat- 30
- ing with the body portion through openings adjacent the table through which openings the arms of the patient may extend, arm rests consisting of spaced slat members in said compartments and passages communicating the lower heat chamber of said body portion of the cabinet with said auxiliary compartments, whereby the heat from said heat chamber will pass upwardly into said compartments around the arms of the patient, and electro-therapeutic light treating means arranged in the upper portions of the body of the cabinet and said compartments. 35
6. A therapeutic bath cabinet of the kind described comprising a body portion having an entrance opening at one end, a table upon which the patient may lie insertable through said opening into said cabinet and dividing said body portion into upper and lower chambers, a heating means in the lower chamber of said cabinet, auxiliary compartments on each side of the cabinet and communicating with the body portion through openings adjacent the table through which openings the arms of the patient may extend, arm rests in said compartments, said compartments having openings in the lower portion thereof communicating with said heat chamber, whereby the heat will ascend in the compartments around the arms of the patient, and means for controlling the passage of heat through said openings. 40

In testimony whereof, I have hereunto set my hand.

MARIE F. HASEMEIER.
